UNITED STATES PATENT OFFICE

ADOLPH STORM AND THOR THORSEN, OF MINNEAPOLIS, MINNESOTA, ASSIGNEES TO
STORM MANUFACTURING CO., INC., OF MINNEAPOLIS, MINNESOTA, A CORPORATION
OF MINNESOTA

CLUTCH

Application filed February 18, 1931. Serial No. 516,646.

Our present invention relates to clutches, and more particularly to a sliding key clutch intended for general use but especially designed for use in connection with the transmission mechanism for lathes, grinders, boring machines and the like.

The object of the invention is the provision of a clutch that is simple and positive in its action, easy to operate, and of comparatively small cost to manufacture.

The invention is a continuation in part of the Adolph Storm application filed September 14th, 1929, under Serial Number 392,649, and entitled "Boring machine".

Generally stated, the invention consists of the novel construction and arrangement of parts hereinafter described and defined in the claim.

In the accompanying drawing, which illustrates the invention, like characters indicate like parts throughout the several views.

Referring to the drawing:

Fig. 1 is a view partly in elevation and partly in central vertical section showing the invention embodied in a variable speed transmission mechanism of a boring machine;

Fig. 2 is a fragmentary detail view in section taken on the line 2-2 of Fig. 1;

Fig. 3 is a view partly in plan and partly in section taken on the line 3-3 of Fig. 1; and

Fig. 4 is a view partly in elevation and partly in longitudinal central section showing the invention embodied in the transmission mechanism for a lathe.

Referring first to the invention as shown in Figs. 1 to 3 inclusive, it is important to note the following parts of a variable speed transmission mechanism, to-wit: an upright driven feed shaft 5, journaled in a bearing head 6, and a lower collar 7 applied to the shaft 5 and arranged to engage the under side of said head and prevent lifting movement of said shaft. A pair of differential spur pinions 8 and 9 are loosely mounted on the shaft 5 and in respect to each other, supported on the bearing head 6, and held against lifting movement therefrom by an upper collar 10, secured to the shaft 5 by a press fit. These spur pinions 8 and 9 mesh with a pair of

connected differential spur gears 11 and 12 respectively.

The improved clutch includes a flat sliding key 13, mounted in a keyway 14 formed in the shaft 5 and extends upward from the collar 7 through the upper end of the shaft 5. This sliding key 13 is end-wise shiftable in the keyway 14 from neutral to a position in which it connects either one of the pinions 8 and 9 to the feed shaft 5. Said key 13 has a long body member 15 which lies entirely within the keyway 14 and is connected to a key shifter 16 by a loose hinge 17. This shifter 16 is in the form of a relatively long sleeve, telescoped onto the upper end of the feed shaft 5 for axial sliding movement, and has on its upper end a hand piece or knob 18.

The hinge 17 is of novel construction and includes a radial pin secured by a press fit in the shifter 16, and a notch in the front edge of the key body 15 into which said pin projects. It will be noted that the formation of the hinge notch, and the key body 15 in the keyway 14, is such as to permit the required hinge movement of said key.

A leaf spring 19, attached to the back of the key body 15, is arranged to slide on the feed shaft 5 at the bottom of the keyway 14, and yieldingly holds said key in an operative position. The outward movement of the shifter 16 on the feed shaft 5 is limited by a slot and screw connection 20. Internal keyways 21 and 22, formed in the pinions 8 and 9 respectively, are arranged to receive the key 13, when endwise positioned to enter either one thereof and brought into registration therewith under the rotation of the feed shaft 5.

Interposed between the pinions 8 and 9 is a cam-acting collar 23 with which the key 13 engages during its shifting movement from the keyway 21 to the keyway 22, or vice versa. The purpose of this cam-acting collar 23 is to completely cam the key 13 out of the keyway in which it extends before the same is permitted to be projected by the spring 19 into the other keyway.

Obviously, by manipulating the shifter 16, the key 13 may be very quickly shifted endwise on the feed shaft 5 from neutral to con-

nect either one of the pinions 8 or 9 to the feed shaft 5. When the key 13 is in neutral, it is in contact with the bearing head 6 and held thereby completely within the keyway 14. The engagement of the shifter 16 with the collar 10 positions the key 13 in neutral position.

A spring pressed friction ball 24, carried by the shifter 16, and cooperating longitudinally spaced seats 25, in the feed shaft 5, yieldingly hold the shifter 16 in either keyway 21 or 22.

The above described variable speed transmission mechanism is designed for use in connection with a boring machine, as shown and described in the heretofore identified application.

Referring now to the use of the improved clutch as shown in Fig. 4, wherein the transmission mechanism is designed for use in connection with a lathe, and of the parts thereof fragmentarily illustrated, the numeral 26 indicates the carriage feed screw journaled in a pair of axially spaced bearings 27 and 28, on the bed of the machine, and a driving gear 29. This gear 29 is loosely journaled on the feed screw 26 and held against axial movement thereon between the bearing 27 and the collar 30, held on said shaft by a press fit.

The pinion 26' on the feed screw 26 is for use in connection with a hand feed for said screw.

The improved clutch, illustrated in Fig. 4, is arranged to connect the feed screw 26 to the driving gear 29, at will. As the clutch in this illustration is identical with the clutch heretofore described in detail, it is thought for the sake of brevity that the simple application of the following designating numerals to the various parts thereof will be sufficient. To-wit: sliding key 31, its body 32, keyway 33 in the feed screw 26, internal keyway 34 in the hub of the gear 29, shifter 35 and its knob or hand piece 36, loose hinge 37, spring 38, and slot and pin connection 39.

When the shifter 35 is in its extreme outermost position and stopped by the connection 39, the key 32 is yieldingly held in the keyway 34 by the spring 38, and connects the feed screw 26 to the gear 29. The inward movement of the shifter 35 is limited by its engagement with the collar 30, and positions the key 31 in neutral, wherein the same is held by the bearing 27 entirely within the keyway 33.

From the above description, it is evident that the improved clutch may be set or released, while the driving members are in motion, simply by manipulating the key shifter. The radial movement of the key into the keyway of the driven member, is very positive in its action and is easily brought into registration therewith.

The drawing illustrates a commercial form

of the invention, but it will be understood that the same is capable of certain modifications as to details of construction, arrangement and combination of parts, within the scope of the invention herein disclosed.

70

What we claim is:

The combination with a shaft, a wheel loose on the shaft, one of which is driven, said wheel being axially spaced from the outer end of the shaft, and a member on the shaft at the inner end of the hub of the wheel, of a clutch for connecting the wheel to the shaft comprising an external keyway in the projecting end of the shaft and extending through the wheel and into the member, an internal keyway in the wheel, extending through the inner end of its hub and closed by the member, a tubular key shifter telescoped onto the projecting end of the shaft and having a key body the outer end portion of which extends into said shifter and is hingedly connected thereto and mounted in the keyway in the shaft, said key body having on its inner end an outwardly and radially projecting key, and a spring compressed between the shaft and key body and under strain to move the key body and project the key into the keyway in the wheel to connect the wheel to the shaft, said shifter being operable to move the key body endwise toward the member to cause the key to engage the member, be cammed thereby out of the keyway in the wheel, into the keyway in the shaft and into the member to release the wheel from the shaft and be held inoperative by the member.

In testimony whereof we affix our signatures.

ADOLPH STORM.
THOR THORSEN.
